(57) **CLAIM**

The ornamental design for a hinge, as shown and described.

DESCRIPTION

FIG. 1 is an isometric view of a hinge, as viewed from the top, front and right sides, and according to a first embodiment;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof;

FIG. 7 is a rear elevation view thereof;

FIG. 8 is an isometric view thereof as viewed from the bottom, front and left sides; and

FIG. 9 is an isometric view thereof as viewed from the top, front and right sides, wherein the hinge is shown in a rotated state.

FIG. 10 is an isometric view of a hinge, as viewed from the top, front and right sides, and according to a second embodiment;

FIG. 11 is a top plan view thereof;

FIG. 12 is a bottom plan view thereof;

FIG. 13 is a left side elevation view thereof;

FIG. 14 is a right side elevation view thereof;

FIG. 15 is a front elevation view thereof;

FIG. 16 is a rear elevation view thereof;

FIG. 17 is an isometric view thereof as viewed from the bottom, front and left sides; and

FIG. 18 is an isometric view thereof as viewed from the top, front and right sides, wherein the hinge is shown in a rotated state.

The broken line showing of the hinge is for the purpose of illustrating portions of the hinge and forms no part of the claimed design.
